IGNITION PLUG FOR INTERNAL-
COMBUSTION ENGINESJacques Bleuze, Paris, France, assignor to Com-
pagnie Generale de Telegraphie Sans Fil, a cor-
poration of France

Application October 18, 1951, Serial No. 251,937

Claims priority, application France
October 26, 1950

6 Claims. (Cl. 315—41)

1

The present invention refers to sparking plugs for electric sparks such as the ignition plugs for internal combustion engines. It more particularly covers the ignition systems in which the feeding is made from a generator giving a very steep wave front.

The engine ignition plugs used so far are well known. The ignition plugs include a metallic envelope bearing one or several electrodes, and a central conductor insulated from the envelope, in which it is engaged so that one of its ends be disposed close to the said electrodes. A dielectric mass fills a part of the envelope, blocking it up hermetically. Its purpose is to ensure the plug air-tightness and to electrically insulate the said central conductor which passes through it. When a high voltage is abruptly applied between the envelope and the central conductor, a spark flashes between the latter and the one or several electrodes supported by the envelope, so allowing to ignite the air-carburetant mixture in the cylinder of an explosion engine.

The said dielectric mass therefore must stand against high electric voltages. It also must stand against abrupt thermic shocks and considerable mechanical strains, due to the high temperatures and strong pressures produced by the explosion of the air-carburetant mixture.

Furthermore, the mass of electric insulation, owing to its very nature, has a very small thermic conductibility (of the order of one thousand times inferior to the thermic conductibility of the usual metals). Therefore, this insulation heats up during the working of the engine, and reaches a very high temperature of steady working, which entails very serious inconveniences. Indeed, at high temperatures, the electric resistance of the insulation decreases exponentially with respect to the temperature, and may fall to very small values. This limits the performances of the engines using the ignition systems such as "Delco" or "magneto," which produce voltage wave fronts of 10^5 to 10^6 volts/second, and can ensure a correct ignition but as long as the insulation resistance of the spark plug is superior to 10^6 to 10^5 ohms. This fact limits the acceptable temperature of steady working of the ignition plug, and whereby, imposes working limits to the engine. This inconvenience is attenuated by the utilisation of electronic circuit breaking or electrostatic ignition systems. These systems produce very steep wave fronts, in the range of 10^{10} to 10^{11} volts/second and function correctly with small insulation resistances of the order of 10^3 ohms.

These systems allow to push the steady working of the engines more. However, at the high rates of steady working, a very serious inconvenience happens, due to the very construction

2

of the ignition plugs. Indeed, a very high temperature is applied to the point of the central conductor by the fact of the bad thermic conductibility of the insulator which bears it. The temperature of that point can wherefore become high enough as to provoke untimely ignitions (back flame), which are injurious for the good working of the engine, and let it rapidly go out of use.

10 The object of the present invention is a new type of ignition plug, in which the heating of the point of the central conductor is sufficiently limited to avoid the auto-ignition accident, and allow a correct working on engines having a high rate of steady working.

Another object of the invention is a new type of ignition plug of more strongly built and more stable making, in which namely the electric insulator is no more necessary to ensure the air tightness of that ignition plug.

25 According to the invention, the new type of ignition plug, intended more particularly to work with an electrostatic feeding, is characterized by the presence of an organ joining the point of the central conductor to the envelope of the ignition plug, this organ being a good heat conductor and also offering a high impedance for the shock wave of the voltage impulses as supplied by the said feeding. Preferably, this organ 30 is constituted by a metallic piece, the form of which is such as to present a certain coefficient of self-induction. This coefficient is so adjusted that the shock wave may give a voltage between the ends of the metallic piece, sufficient to let a spark flash between the electrodes of the ignition plug.

According to a first mode of embodiment, the ignition plug includes a metallic envelope and a central conductor electrically insulated from the latter. Furthermore, it includes a metallic piece having the form of a solenoid whose spires are insulated from each other by an insulating material placed between them, this piece being disposed in the body of the ignition plug, coaxially with the central conductor. It is fixed at one end of that central conductor on one hand and to the ignition plug body on the other hand.

According to a second way of embodiment, the said piece will be constituted by a metallic solenoid including a magnetic core coaxial to the central conductor, this core being made of a fire proof and insulating magnetic material such as the ferrites.

50 According to a third mode of embodiment, the said piece is constituted by two coaxial cylinders disposed in the ignition plug body. The internal cylinder is fixed to the central conductor near its point, the external cylinder is supported by a

holder formed by the body of the ignition plug, these two cylinders being joined together at their free end, by a metallic piece, so as to form an inner side ensuring the air-tightness of the ignition plug.

The enclosed figures, as non-limiting examples, will allow the better understanding of the invention.

The Figure 1 shows schematically a classical ignition plug in longitudinal section.

The Figure 2 shows the theoretical diagram of the invention.

The Figures 3, 4 and 5, schematically, show three modes of embodiment of ignition plugs, in longitudinal section, according to the invention.

The classical ignition plug represented on Figure 1 includes a metallic envelope 3, a central conductor 2 insulated from the envelope by an insulator 4. The lower end of the central conductor 2 and that of the body 3, constitute the electrodes 1 between which the spark flashes.

On the Figure 2, the ignition plug has been represented by a spark gap 1. This spark gap is fed by a generator 10 loading a capacitor C and the spark flashes in 1 when closing the switch D (which, in the engine, is a distributor driven by an appropriated mechanism).

The inductance connected between the point A and the earth does not short-circuit the spark gap, the wave front being blocked by this inductance. But if it is conveniently embodied, the latter may, by thermic conductivity, easily evacuate the heat from the point A.

In order that 3 makes a good blocking of the wave front, the inductance value should be as high as possible. The value of this inductance will be easily increased, without increasing its size, by using fire proof and insulating magnetic cores, such as ferrites, agglomerated iron powders, etc. This permits to give the inductance a compact form allowing better to evacuate the heat from the point of the central conductor.

The ignition plug represented on Figure 3 includes a metallic envelope 1 in which the central conductor is placed. The latter, as well as the envelope are ended by the electrodes 4 disposed in front of each other. A metallic piece 3, of solenoidal form, whose spires are insulated from each other by an insulating material 6, is fixed one end at the extremity of the central conductor in 8 and the other end at the envelope in 5. The central conductor clears out in a cylindrical hollow 12 lined up with an insulating coat 7 which, together with the piece 11 fixed to the central conductor and bearing against this coat, ensures the air-tightness of the ignition plug.

The ignition plug represented on Figure 4 includes the same elements as in Figure 3, but furthermore, it includes a magnetic core 13 disposed in the solenoid 3 so increasing its coefficient of self induction, and allowing to give to the solenoid a more compact form, so as to decrease the length of thermic conduction between the point of the central conductor and the envelope of the ignition plug.

The ignition plug represented on the Figure 5 includes a metallic envelope 1 and a central conductor 2 ended by electrodes 4 disposed in front of each other, a first metallic cylinder 3 fixed in 8 at the end of the central conductor, a second cylinder 14, coaxial to the first one as well as to the central conductor. This second cylinder bears against the envelope upon a conical bearing 5 and is joined to the cylinder 3 by a metallic annular piece 13. A coat of fireproof insulating

material 7 is laid in the cylindrical cavity 12 as well as between the envelope 1 and the cylinder 14. This insulating coat at the same time isolates the central conductor 2 from the sides of the cylinder 3 between which it is laid. It also isolates the terminal piece 11 fixed to the central conductor 2, from the envelope 1. In this embodiment, the air-tightness of the ignition plug is ensured by the two coaxial cylinders 3 and 4 and the piece 13 which joins them, and these three pieces form a short length of short-circuited coaxial, equivalent to an inductance increased by a coat of fire proof and insulating magnetic material 6, laid between the two cylinders. It may be noticed that the present invention allows to embody ignition plugs, the air-tightness of which is ensured by metallic pieces, a fact which overturns the technics of ignition plug construction in which their air-tightness was ensured by an insulating mass.

What I claim is:

1. An ignition plug more particularly intended for internal combustion engines, including a metallic envelope, a central conductor electrically insulated from this envelope, and a helical piece offering a substantial self induction coefficient, this piece joining one end of the said central conductor to the envelope of the ignition plug.

2. An ignition plug according to claim 1, in which the said helical piece is made in the form of a solenoid.

3. An ignition plug according to claim 1, in which the said piece has the form of a solenoid, the spires of which are insulated from each other by an insulating material disposed between them.

4. An ignition plug according to claim 1, in which the said piece includes a core of insulating magnetic material, so increasing the self induction coefficient of that piece.

5. A spark plug for use with an internal combustion engine employing a direct current voltage impulse system comprising in combination a metallic tubular envelope, a central conductor located in said envelope and insulated therefrom, one end of said central conductor forming with the corresponding edge of said envelope a spark gap, and a metallic piece presenting two ends and looped so as to present a substantial self-inductance, one of the ends of said piece being fastened to the end of the central conductor near the spark gap and the second end of said piece being fastened to said envelope.

6. A spark plug for use with an internal combustion engine employing a direct current voltage impulse system comprising in combination a metallic tubular envelope, a central conductor located in said envelope and insulated therefrom, one end of said central conductor forming with the corresponding edge of said envelope a spark gap, and a metallic helix surrounding said central conductor, one of the ends of said helix being fastened to the end of the central conductor near the spark gap and the second end of said helix being fastened to said envelope.
